UNITED STATES PATENT OFFICE.

GEORGE E. HEIDBREDER, OF QUINCY, ILLINOIS.

COAL AND GAS RANGE.

1,208,314.

Specification of Letters Patent. Patented Dec. 12, 1916.

Application filed September 14, 1916. Serial No. 120,124.

To all whom it may concern:

Be it known that I, GEORGE E. HEIDBREDER, a citizen of the United States, residing at Quincy, in the county of Adams, 5 State of Illinois, have invented a new and useful Coal and Gas Range; and I do hereby declare the following to be a full, clear, and exact description of the invention, such as will enable others skilled in the art to 10 which it appertains to make and use the same.

This invention relates to an improved combination coal and gas range, and one of the objects of the invention is to provide a 15 device of this kind, which is simple, efficient and practical in construction and so constructed that it may be easily converted, whereby either coal or gas may be used.

Another object of the invention is to improve the coal and gas ranges shown, set 20 forth and claimed in the prior patents to George E. Heidbreder issued respectively October 19, 1915 and March 28, 1916, Patent Nos. 1,156,999 and 1,177,244.

25 A further object of the invention is to provide a passage for the products of combustion from the fire-pot leading over the oven and down adjacent the end of the oven opposite the fire-pot, under the oven, and 30 deflected into and through an exhaust flue.

A further object of the invention is the provision of a gas chamber and burner therein and provided with passages of communication with the oven, in combination with 35 an exhaust passage from the oven communicating with the flue for the products of combustion from the fire-pot, whereby should the heat in the oven from the gas chamber increase, it is automatically carried off 40 through the said flue and then under the oven and deflected into and through the exhaust flue.

A further object of the invention is to provide means for controlling the passage of 45 heat from the oven to and through the said flue.

A further object of the invention is to provide means for controlling the gas burner and the controlling damper of the oven simultaneously.

In practical fields the details of construction may necessitate alterations falling within the scope of what is claimed.

The invention comprises further features 55 and combinations of parts, as hereinafter

set forth, shown in the drawings and claimed.

In the drawings:—Figure 1 is a plan view of the improved combination coal and gas range constructed in accordance with the 60 invention. Fig. 2 is a vertical sectional view on line 2—2 of Fig. 1. Fig. 3 is a transverse sectional view on line 3—3 of Fig. 2. Fig. 4 is a vertical sectional view on line 4—4 of Fig. 2.

65 Referring more especially to the drawings, 1 designates a casing of the coal and gas range provided with the usual fire-pot 2, the grate bars 3 and the ash-pit 4.

The top plate 5 has one-half provided 70 with the usual cooking holes 6 and cover plates 7. The other half of the top plate merges downwardly and laterally and upwardly forming a depression 8 for the usual burners 9, over which the conventional supporting bars 10 for pans and the like are arranged. The burners 9 are connected by the valve connections 11 to the usual gas supply pipe 12.

Extending from the fire-pot and over the 80 oven 13 is a passage or flue 14, which merges into the flue or passage 15 at the end of the range opposite the fire-pot. It is to be noted that the passage 14 where it communicates with the passage 15 extends under the gas 85 burner space 8, whereby said space, may be heated, so that pans or articles of food may be kept warm when burning coal in the fire-pot and not using said burners 9.

The flue or passage 15 does not extend to 90 the front of the oven at its lower part, but merges at the back into the flue or space 16 under the bottom of the oven 13, and communicating with this space or flue 16, by the port 17, is an exhaust flue or passage 18 95 at the back of the oven, and to the flange 19 of the rear part of the top plate of the casing of the range the usual smoke flue or pipe (not shown) may be connected.

100 Adjacent one side of the port 17, a deflector plate 20 is secured, extending angularly and half way across the space or flue 16, so as to deflect the products of combustion over the entire bottom sheet of the oven and out through the port 17 and through the 105 flue 18. Between the bottom sheet of the casing of the range and the bottom wall or sheet of the flue 16 is a gas burner space 21, in which a gas burner 22 is arranged.

110 The gas supply pipe 23 is provided with

the usual connection 24 with said burner 22, which connection is provided with the usual gas cock or valve 25, to the valve stem of which an arm 26 is connected, and by grasping the hand piece 27 of said valve cock the gas may be turned on.

Secured in any suitable manner to the under face of the bottom sheet of the flue or space 16 is a conical deflector plate or sheet 10 28, which deflects the heat from the burner in opposite directions and toward the flues or passages 29 and 30 at opposite ends of the space or passage 16.

The plate 31, together with the walls 32 15 and 33, form the opposite sides of the flue 30. The wall 33 of one end of the oven 13 has ports 34 communicating with the flue 30 and said oven, so that the heat from the burner 22 may pass into the oven. The wall 20 35 extends from the front portion only of the oven wall 36 to end range wall 37, and the lower forward portion of this wall 35 forms the heat flue 29 from the burner 22, while the rearwardly extending portion 38 25 of the wall 35 extends substantially from the forward portion of the oven wall 36 to the rear of said wall, thereby forming the space 39 but leaves a large part of the flue 15 unobstructed, as shown in Fig. 4.

30 The lower part of the wall 36 adjacent the space 39 is provided with elongated openings 40, through which the heat from the space 39 may pass into the oven. The upper edges of the openings 40 have flanges 41, 35 which, as the heat from the burner ascends into the space 39, deflects the heat toward the upper surface of the bottom sheet of the oven.

An arched plate 42, shown in dotted lines 40 in Fig. 2 and in section in Fig. 3, is secured on the rear sheet 43 of the range, thereby forming the space or passage 44.

The rear sheet 43 of the range is provided with ports or openings 45 and 46. The port 45 45 forms communication between the space 44 and the oven, while the opening or port 46 forms communication between the space 44 and the flue or passage 15.

50 Mounted in bearings of the plate 42 is a rock shaft or rod 48 having a crank arm 49 at one end, and provided with a damper plate 50, which is of sufficient length to cover both openings 45 and 46. A rod 51 has one end connected to the crank 49, and 55 the other end to the arm 26 of the stem of the gas or valve cock 25. It is to be noted that when manipulating the valve cock 25 to admit gas to be lighted, the damper plate 50 is simultaneously opened, thereby 60 uncovering the openings 45 and 46 and allowing the heat in the oven to pass through the opening 45 into the space 44, through the opening 46 into the lower part of the passage or flue 15, and as there is a draft 65 downwardly through the flue 15 into the

space 16, the excess heat from the oven will pass off through the flue 16 under the oven sheet and out through the exhaust flue.

When burning coal in the fire-pot, the damper plate 50 may be closed, thereby covering the ports 45 and 46 to prevent the escape of the heat in the oven. However, when burning coal in the fire-pot and the heat in the oven should become too great, the excess heat may be allowed to escape, by 70 detaching the rod 51 from the crank 49 of the rock rod 49, and opening the damper plate, allowing the excess heat to pass into the flue 15 and into the flue 16 and thence through the exhaust flue 18. 80

The bottom sheet 52 of the gas burner space 21 is provided with two sets of perforations or apertures 53, to permit the intake of air, in order that proper combustion for the burner 22 may be had, and so that the 85 heat will travel upwardly into the oven. In other words, by providing these air holes, a draft is created, which causes the heat from the burner to ascend into the flues 29 and 30.

90 There is an essential feature or result attained by permitting the escape of the excess heat in the oven, for instance, in that the oven is not too quickly cooled. For example, even though the excess heat is passing out through the ports or openings 45 and 46, the 95 intensity of such heat is not very much decreased; therefore, when such heat is passing through the lower part of the flue 15 and through the flue 16, the heat acts upon one of the end walls of the oven and the bottom sheet of the oven, and for this reason the heat in the oven does not begin to lessen until the damper plate 50 is open for a considerable length of time.

105 A damper 54 is mounted in the exhaust flue 18, and when the damper is closed the heat from the oven, that is the excess heat, may pass through the flue 15 and into the space 16, by opening the damper plate 50. In other words, by opening the damper 50 110 and closing the damper 54, the heat in the oven is given room to expand, and the excess of this expanded heat may be allowed to pass off by opening the damper 54 partially or completely. 115

The invention having been set forth, what is claimed as new and useful is—

1. In a coal and gas range, the combination of a range casing having a fire-pot and an oven, of a flue extending from the fire-pot over the oven and down and under said oven and provided with an exhaust flue, a burner space under the flue which extends under the oven, a burner in said space, said burner space having upwardly extending flues, one at each end, in communication with the oven, and means of communication between the oven and that portion of the first flue which extends down adjacent one end of the oven. 120 125 130

2. In a coal and gas range, the combination of a range casing having a fire-pot and an oven, of a flue extending from the fire-pot across the top of the oven and down adjacent one end and under the oven and terminating in an exhaust flue, a burner space under that portion of the flue under the oven and provided with flues, one at each end, in communication with said oven, a burner in said space provided with a gas cock, a space of communication between the back portion of the oven and the downwardly extending part of the first flue, a damper controlling said communication between the oven and the downwardly extending part of the first flue. 70
3. In a coal and gas range, the combination of a range casing having a fire-pot and an oven, of a flue extending from the fire-pot across the top of the oven and down adjacent one end and under the oven and terminating in an exhaust flue, a burner space under that portion of the flue under the oven and provided with flues, one at each end, in communication with said oven, a burner in said space provided with a gas cock, a space of communication between the back portion of the oven and the downwardly extending part of the first flue, a damper controlling said communication between the oven and the downwardly extending part of the first flue, and a connection between said damper and the gas cock whereby the gas cock and the damper may be operated simultaneously. 75
4. In a coal and gas range, the combination of a range casing having a fire-pot and an oven, of a flue extending from the fire-pot across the top of the oven and down adjacent one end and under the oven and terminating in an exhaust flue, a burner space under that portion of the flue under the oven and provided with flues, one at each end, in communication with said oven, a burner in said space provided with a gas cock, a space of communication between the back portion of the oven and the downwardly extending part of the first flue, a damper controlling said communication between the oven and the downwardly extending part of the first flue, and a connection between said damper and the gas cock whereby the gas cock and the damper may be operated simultaneously. 80
5. In a coal and gas range, the combination of a range casing having a fire-pot and an oven, of a flue extending from the fire-pot across the top and down adjacent one end and under the bottom of the oven and terminating in a discharge flue, a burner space under that portion of the flue under the oven and having flues at its opposite ends, ports of communication between the opposite ends of the oven and said flues of said burner space, said ports having flanges to deflect the heat from the burner space down upon the bottom sheet of the oven, 85 and means of communication between the oven and the downwardly extending part of the first flue, whereby the excess heat of the oven may be allowed to expand, thereby gradually reducing the heat in the oven. 90
6. In a coal and gas range, the combination of a range casing having a fire-pot and an oven, of a flue extending from the fire-pot across the top and down adjacent one end and under the bottom of the oven and terminating in an exhaust flue, a burner space under that portion of the flue under the oven and having flues at its opposite ends, ports of communication between the opposite ends of the oven and said flues of said burner space, said ports having flanges to deflect the heat from the burner space down upon the bottom sheet of the oven, 95 and means of communication between the oven and the downwardly extending part of the first flue, whereby the excess heat of the oven may be allowed to expand, thereby gradually reducing the heat in the oven. 100
7. In a coal and gas range, the combination of a range casing having a fire-pot and an oven, of a flue extending from the fire-pot across the top and down adjacent one end and under the bottom of the oven and terminating in an exhaust flue, a burner space under that portion of the flue under the oven and having flues at its opposite ends, ports of communication between the opposite ends of the oven and said flues of said burner space, said ports having flanges to deflect the heat from the burner space down upon the bottom sheet of the oven, 105 means of communication between the oven and the downwardly extending part of the first flue, whereby the excess heat of the oven may be allowed to expand, thereby gradually reducing the heat in the oven, said exhaust flue of the first flue having a damper to control the excess of the expanded heat from the oven. 110
8. In a coal and gas range, the combination of a range casing having a fire-pot and an oven, of a flue extending from the fire-pot across the top and down adjacent one end and under the bottom of the oven and terminating in an exhaust flue, a burner space under that portion of the flue under the oven and having flues at its opposite ends, ports of communication between the opposite ends of the oven and said flues of said burner space, said ports having flanges to deflect the heat from the burner space down upon the bottom sheet of the oven, 115 means of communication between the oven and the downwardly extending part of the first flue, whereby the excess heat of the oven may be allowed to expand, thereby gradually reducing the heat in the oven, said exhaust flue of the first flue having a damper to control the excess of the expanded heat from the oven. 120
9. In a coal and gas range, the combination of a range casing having a fire-pot and an oven, of a flue extending from the fire-pot across the top and down adjacent one end and under the bottom of the oven and terminating in an exhaust flue, a burner space under that portion of the flue under the oven and having flues at its opposite ends, ports of communication between the opposite ends of the oven and said flues of said burner space, said ports having flanges to deflect the heat from the burner space down upon the bottom sheet of the oven, 125 means of communication between the oven and the downwardly extending part of the first flue, whereby the excess heat of the oven may be allowed to expand, thereby gradually reducing the heat in the oven, said exhaust flue of the first flue having a damper to control the excess of the expanded heat from the oven. 130

- and the downwardly extending part of the first flue, whereby the excess heat of the oven may be allowed to expand, thereby gradually reducing the heat in the oven, 5 said exhaust flue of the first flue having a damper to control the excess of the expanded heat from the oven, said means of communication between the back portion of the oven and said downwardly extending part 10 of the first flue having a damper to control the expansion of the heat in the oven, said burner having a valve cock, and a connection between the valve cock and the damper whereby both may be simultaneously actuated. 15
9. In a coal and gas range, the combination of a range casing having a fire-pot and an oven, of a flue extending from the fire-pot across the top and down adjacent one end and under the bottom of the oven and terminating in an exhaust flue, a burner space under that portion of the flue under the oven and having flues at its opposite ends, ports of communication 20 between the opposite ends of the oven and said flues of said burner space, said ports having flanges to deflect the heat from the

burner space down upon the bottom sheet of the oven, means of communication between the oven and the downwardly extending part of the first flue, whereby the excess heat of the oven may be allowed to expand, thereby gradually reducing the heat in the oven, said exhaust flue of the first flue having a damper to control the excess of the expanded heat from the oven, said means of communication between the back portion of the oven and said downwardly extending part of the first flue having a damper to control the expansion of the heat 25 in the oven, said burner having a valve cock, a connection between the valve cock and the damper whereby both may be simultaneously actuated, and a deflector plate secured in the burner space to the under face of the flue sheet under the oven to deflect the heat into the flues of the burner space. 30

In testimony whereof I have signed my name to this specification in the presence of two subscribing witnesses.
